A. F. VOLZ, JR.
METHOD AND APPARATUS FOR FORMING MONOLITHIC STRUCTURES.
APPLICATION FILED DEC. 18, 1919.
1,337,493. Patented Apr. 20, 1920.

UNITED STATES PATENT OFFICE.

ALEXANDER F. VOLZ, JR., OF ST. LOUIS, MISSOURI.

METHOD AND APPARATUS FOR FORMING MONOLITHIC STRUCTURES.

1,337,493.

Specification of Letters Patent. Patented Apr. 20, 1920.

Application filed December 18, 1919. Serial No. 845,697.

To all whom it may concern:

Be it known that I, ALEXANDER F. VOLZ, Jr., a citizen of the United States, residing at St. Louis, State of Missouri, have invented certain new and useful Improvements in Methods and Apparatus for Forming Monolithic Structures; and I do declare the following to be a full, clear, and exact description of the invention, such as will enable others skilled in the art to which it appertains to make and use the same.

This invention relates to an improved method and apparatus for forming monolithic structures.

The principal objects are to provide a mold in which matrices are mounted on the inner faces in such a manner that when the structure forming plastic is poured or pressed into the mold, desired phrases, numerals, emblems, figures, or names will be formed on the structure.

A further object is to provide a mold for various shaped monolithic structures in which the letter and emblem forming matrices are mounted in the mold in such a manner that they will shift position in proportion to the shrinkage of the structure forming plastic.

With the above and other objects in view the invention consists of the novel arrangement and application of parts as will be more fully described.

I attain these objects by the construction and arrangement illustrated in the accompanying drawings in which,—

Figure 1 is a perspective view of two sections of the mold;

Fig. 2 is a sectional view taken on the line 2—2 of Fig. 1; and

Fig. 3 is a horizontal sectional view of a modified form of attaching matrices to a mold.

Similar reference numerals designate similar parts throughout the drawings.

While this mold is primarily adapted for use in forming tomb-stones it may well be used in molding any number of other monolithic structures regardless of the shape and size.

Reference is now had to the drawing in which is shown vertical side walls 1 of a mold, said walls being shown provided with a number of types of matrices. When it is desired to form on a monument or other structure to be molded, a design, phrase or word, the side wall or walls of the mold

are provided with recesses at 1^a the desired points. The design or emblem to be formed on the structure is duplicated on one face of a matrix or block 2, said block 2 being 60 then positioned in one of the recesses in the mold and surrounded by a plastic composition 3 which primarily serves to retain the block in its proper position. This plastic composition which is preferably stiff clay 65 possesses substantially the same qualities of shrinkage as the structure forming material which is poured into the mold. From this it is readily seen that the structure forming material being poured into the mold before 70 the plastic composition 3 sets, the matrices will be permitted to move the proper distance in proportion to the shrinkage of the structure forming plastic.

In molds constructed in the usual manner 75 the matrices are rigidly mounted on the mold with the result that when the structure forming material shrinks the letters formed on the structure are invariably out of shape. With the construction herein de- 80 scribed the matrices are allowed to move with the shrinking of the structure forming material and the result is that clear sharp letters or emblems are formed on the structure.

Quite often a structure is to be formed in which the surface will be irregular, and to provide means for forming letters or phrases on this surface, I provide a mold constructed somewhat similar to that illustrated in Fig. 90 3. In this form the wall of the mold is curved to conform to the desired curvature of the structure and is provided with a recess 4 of uniform depth throughout. The word or phrase desired is formed by placing a number of letter-carrying matrices in a suitable frame (not shown). A relatively thick layer 1 of plastic composition 5 is attached to the reverse sides of the matrices and then as a unit is inserted into the recess 100 4 as shown in Fig. 3. The space around this unit and between the matrices is filled with a plastic composition 6 of the same nature as said layer 5. It is readily seen that this unit may be curved to conform perfectly 105 with the irregularities of the surface upon which the phrases or words are to be formed.

The method employed in forming structures having comparatively regular surfaces may be stated as consisting in inserting a 110 matrix or matrices in plastic material and pouring into the mold the structure form-

ing material. The structure forming material is necessarily poured into the mold before the first named plastic sets. The two plastic materials possessing substantially the same qualities of shrinkage, will permit proper shifting of the matrices as hereinbefore set forth.

When inserting matrices as illustrated in Fig. 3 a suitable frame is employed to permit proper positioning of the matrices, which are then mounted on a layer of plastic composition and as a unit are inserted into the curve of the mold. The space around the matrices is filled with a plastic composition similar to the layer 5 and serves to retain the matrices in proper position for forming the phrases or words on the structure. It is readily seen from observation of Fig. 1 that these matrices may be used to form raised letters or emblems on a monolithic structure or may be used to form V or other shaped letters which are flush with the surface of the structure.

From the foregoing description the method and apparatus for forming structures such as that for which it is designed will be readily understood without requiring a more extended explanation.

Various changes in the form, proportion and minor details of construction may be resorted to without departing from the principle or sacrificing any of the advantages of the claimed invention.

I claim:

1. In a mold of the class described, the combination of one side of the mold, matrices disposed on the inner face of said mold, a plastic composition surrounding the matrices and securing them to the wall, said composition possessing approximately the same shrinking qualities as the article forming material whereby the matrices will

be permitted to shift position as the material shrinks.

2. In a mold of the class described, the combination of one side of the mold having a recess in its inner face, matrices disposed in said recess, a plastic composition surrounding the matrices, said composition being shrinkable to approximately the same degree as the article forming material whereby the matrices will be permitted to shift position as said material shrinks.

3. In a mold of the class described for forming an article having a lettered irregular surface, one side of the mold having a recess of uniform depth throughout, a layer of plastic composition, matrices mounted on said layer, said layer and matrices being disposed in said recess, a plastic composition surrounding said matrices and adapted to secure them in said recess, said layer and last named composition possessing approximately the same shrinking qualities as the article forming material whereby the matrices will be permitted to shift position as the last named material shrinks.

4. A method of casting a monolithic structure and forming an imprint thereon consisting in holding a matrix in a mold, by a plastic composition around the matrix and placing the structure forming plastic in the mold before hardening of said first mentioned plastic composition.

5. The method of inserting matrices in a curved mold consisting in assembling the matrices, applying a layer of plastic composition to the reverse sides of said matrices and inserting the matrices and plastic composition as a unit into the curve of the mold before setting of said plastic material.

In testimony whereof I have hereunto set my hand.

ALEXANDER F. VOLZ, JR.
